UNITED STATES PATENT OFFICE.

CARL MIEHLKE, OF HARTFORD, WISCONSIN.

AUTOMATIC DAMPER.

Application filed November 19, 1925. Serial No. 70,019.

This invention relates to automatic dampers or draft regulators.

Objects of this invention are to provide an automatic damper which will control the draft for a furnace, for instance, and maintain the draft at any fixed or desired amount irrespective of fluctuations due to atmospheric conditions.

Further objects are to provide a device which, although substantially instantly responsive, nevertheless does not produce a sudden or violent variation in the draft, but produces a more uniform or gradual variation, such as is needed in furnaces.

An embodiment of the invention is shown in the accompanying drawings, in which:—

Figure 1 is a plan view of the device.

Figure 2 is a sectional elevation thereof.

Figure 3 is a detail of the knife edge pivot for the damper.

Figure 4 is a further detail of the connection between the balancing lever and the valve or disk.

The damper comprises a cylindrical casing 1 into which a pair of pipes 2 and 3 open. These pipes may be connected to the furnace and the chimney, respectively, although the order of connection may be reversed, as the device will work equally well for either connections. The cylindrical member is closed except for the relatively large opening 4 through its top wall. Below this opening a valve or disk 5 is positioned. This valve or disk is preferably made of thin sheet metal so as to keep the weight down and is centrally apertured and receives the bearing member 6 which is shown in greater detail in Figure 4. This bearing member has a relatively large and elongated aperture 7 formed therein and provided with a rounded top. The point 8 of a rod or lever 9 fits loosely into this aperture and provides a pivot bearing for the disk. This rod or lever 9 is bent angularly to provide an upright portion 10 which passes upwardly through the casing 1. It is provided with a pair of knife edges 11 formed, as illustrated in Figure 3, from an integral portion of the lever. These knife edges seat in slots formed in hardened bearing blocks 12. The lever continues outwardly and is provided with an outwardly projecting arm 13 upon which a weight 14 is adjustably mounted, preferably being located in adjusted position by means of a set screw 15.

From the description thus far given, it is apparent that when the draft or suction exceeds a predetermined amount the disk or valve 5 will be drawn downwardly to relieve this suction and restore it to a predetermined value due to the setting of the weight 14. However, if the apparatus consisted only of these parts, the alteration or change from an intense suction to a lesser suction would be too violent and would upset the operation of the furnace and also produce chattering of the device.

In order to make this change more gradual and uniform, a novel mechanism is associated with the disk 5 and controlled by the position of the disk. This mechanism comprises a pin or shaft 16 which slidably passes through bearings carried by the outer end of an arm 17 (see Figure 2). It is preferably provided with a collar 18 adjacent its upper end to prevent the shaft from sliding completely out of the bearings. The lower end of the shaft carries a fan 19, as shown particularly in Figures 1 and 2. This fan is of slightly less diameter than the opening 4 and is normally positioned above the opening when the device is closed. However, when the device opens due to excess suction, the bearing member 6 moves downwardly with the disk 5 and allows the shaft 16 to slide downwardly, such shaft resting upon the bearing member 6. This positions the fan 19 substantially within the opening 4. The fan does not immediately come up to full speed due to the inrushing air, but a certain interval of time elapses before it attains this speed. Consequently the flow of air is at first retarded and is allowed to gradually increase as the fan comes up to speed and offers less and less resistance to the inwardly flowing air.

Further, the fan prevents the discharge of soot or sparks from the device, for if the suction should suddenly cease due to variation in wind pressure, for instance, or to other causes, the air would not be immediately forced out of the opening 4 as the spinning fan would prevent such outward passage until the disk 5 had time to close.

Thus, it will be seen that the fan serves a novel purpose and performs this double function of making a more gradual change from an excessive suction to a gradual suction than could be obtained merely by the valve or disk 5, and also prevents the egress of sparks or soot.

It will be seen that the device may be very easily applied to existing furnaces and that it is wholly automatic in its action and may be set so that it responds to any desired condition.

Although the invention has been described in considerable detail, it is to be understood that the invention may be variously embodied and the scope of the invention is to be determined as claimed.

I claim:

An automatic damper comprising a casing having an inlet pipe and an outlet pipe and

having an opening in its upper side, a disk positioned below said opening and normally closing such opening, means normally tending to hold said disk in closed position, and a fan positioned above said disk and adapted to move downwardly into said opening when said disk is displaced.

In testimony that I claim the foregoing I have hereunto set my hand at Hartford, in the county of Washington and State of Wisconsin.

CARL MIEHLKE.
